UNITED STATES PATENT OFFICE

146,838

DESIGN FOR A CASING FOR HEARING AID APPARATUS

Raleigh E. Tresise, Cleveland Heights, and Paul D. Kendall, Maple Heights, Ohio, assignors to Paraphone Hearing Aid, Inc., Cleveland, Ohio, a corporation of Ohio

Application February 28, 1946, Serial No. 126,982

Term of patent 14 years

(Cl. D58—11)

To all whom it may concern:

Be it known that we, Raleigh E. Tresise and Paul D. Kendall, citizens of the United States, residing, respectively, at Cleveland Heights and Maple Heights, in the county of Cuyahoga and State of Ohio, have invented a new, original, and ornamental Design for a Casing For Hearing Aid Apparatus, of which the following is a specification, reference being had to the accompanying drawing, forming part thereof, wherein Fig. 1 is a side elevational view, Fig. 2 a rear elevational view and Fig. 3 a front elevational view of a casing for hearing aid apparatus, showing our new design. The dominant features of the design reside in the portions illustrated in full lines.

We claim:

The ornamental design for a casing for hearing aid apparatus, as shown and described.

RALEIGH E. TRESISE.
PAUL D. KENDALL.
